GEORGE ANTHONY BUCHANAN, OF TELFORD STATION, PENNSYLVANIA.

Letters Patent No. 94,392, dated August 31, 1869.

IMPROVEMENT IN SHAFT-COUPINGS.

The Schedule referred to in these Letters Patent and making part of the same.

To all whom it may concern:

Be it known that I, GEORGE ANTHONY BUCHANAN, of Telford Station, Montgomery county, State of Pennsylvania, have invented an Improved Coupling for the Shafts or Pole of a Carriage; and I do hereby declare the following to be a full, clear, and exact description of the same.

My invention consists of a carriage-shaft or pole, made in two parts or sections, which are arranged for ready connection to, or disconnection from each other, as fully described hereafter.

In order to enable others skilled in the art to make and apply my invention, I will now proceed to describe its construction and operation, reference being had to the accompanying drawing, which forms a part of this specification, and in which—

Figure 1 is a side view of one of the shafts or pole of a carriage constructed according to my improvement, showing the two parts disconnected;

Figure 2, the same, partly in section, with the two portions coupled together; and

Figure 3, a plan view, also partly in section.

A represents a portion of one of the shafts or pole of a carriage, having at its rear end an eye, a, by means of which it is secured, in the usual manner, to a clip or other device attached to the axle.

The shaft A is divided, at a point adjacent to its rear end, into two portions, b and b', which are arranged, as I will now proceed to describe, so that they can be readily connected together, and as readily disconnected from each other.

In the front end of the section b of the shaft is formed a recess for the reception of a flat tongue, c, of the section b', the latter being maintained in the said recess by means of a tapering or wedge-shaped key, f, which passes through openings in the section b and tongue c.

This key is attached to a steel spring, h, which is

secured to the shaft at a point, i, the said spring being arranged to lie closely to the shaft, with its key inserted into the opening of the same, and being bent upward at its outer end, so that it may be drawn back, as seen in fig. 1, when the section b' of the shaft is to be connected or disconnected.

A principal advantage of my invention is, that it enables the shafts or pole of a carriage to be instantly disconnected from the same should the horses become unmanageable; and to facilitate the operation of the springs h from the driver's seat, each of the said springs may, if desired, be provided with a suitable strap or cord, attached to its outer end.

It will be seen that the spring h accomplishes the twofold purpose of retaining the wedge f in connection with the section b, so that it cannot be lost or mislaid, without interfering with its free removal, and of covering the opening in which the wedge enters, so as to prevent the access of dust and moisture, and the consequent jamming or rusting of the wedge in its place.

I do not claim, broadly, securing the two parts of a shaft by a detachable wedge; but

I claim as my invention, and desire to secure by Letters Patent—

The section b of a carriage-shaft or pole A, jointed to the axle, and having at its end a recess, in combination with a tongue, c, adapted to the recess in the section b, and with a spring, h, provided with a key, f, adapted to openings in the section b and tongue c, as set forth.

In testimony whereof, I have signed my name to this specification, in the presence of two subscribing witnesses.

GEORGE A. BUCHANAN.
